VALVE MECHANISM

Application filed October 31, 1927. Serial No. 230,035.

This invention relates to valve mechanisms, and particularly to new, novel, and positively acting means that can be arranged in the lines of supply leading from respectively 5 different liquid sources and which said means will be characterized by instrumentalities that will permit liquid to be discharged selectively from said sources, so that the liquid from one source may be led from that source 10 and mixed with a determined measure of liquid discharging from another source, or whereby liquid may be positively discharged from either of the sources without being mixed or the least intermingled with the 15 liquid of the other source.

The invention is particularly designed for use in connection with lavatory fixtures of the type wherein provision is made for the delivery of hot and cold water from the customary hot and cold water sources, but it should be understood that this is not to be taken as a limitation and that the invention is to be reviewed in the light of a mixer broadly without regard to the nature of the 25 liquids to be dispensed.

An extremely important object of the invention resides in the provision of means for positively insuring against the slightest intermingling of two liquids when it is desired 30 that but one liquid shall be dispensed.

A further object of the invention resides in the provision of positively functioning means for determining the amount of liquid 35 of one kind to be intermingled with a liquid of another kind and discharged therewith from the mechanism.

A still further object of the invention is to provide a valve mechanism which is simple of construction, positively acting, strong 40 and durable and one which will not easily get out of repair, but which will consist of a novel combination of parts that will allow for quick repairs when needed or a substitution at minimum expense of a new part for 45 a worn one.

A still further object of the invention resides in the provision of mechanism of this character which may be connected respectively with a discharge faucet and a shower head and which will include means common

to the faucet and said shower head for directing the water to either one of these elements.

In the accompanying drawings,

Figure 1 is a view in vertical section through the mechanism with parts shown in 55 elevation and parts broken away.

Figure 2 is a section on line 2—2 of Figure 1;

Figure 3 is a vertical section on line 3—3 of Figure 1 with parts shown in full lines; 60

Figure 4 is a fragmentary sectional view through a portion of the mechanism showing an adjustment of its parts for a delivery of cold water therefrom;

Figure 5 is a view similar to Figure 4, 65 showing an adjustment of the parts for the delivery therefrom of hot and cold water;

Figure 6 is a similar view showing an adjustment of the parts for a discharge of hot water therefrom; 70

Figure 7 is a bottom plan view of the separator;

Figure 8 is a bottom plan view of one of the sleeves.

In carrying the invention into practice, 75 use is made of a valve body 10 having a vertical cylindrical extension 11 rising therefrom. Below the said cylindrical extension 11, the valve body is formed with an inlet duct 12 in communication with a threaded 80 branch 13, the latter adapted to be arranged in the customary manner in a source of hot water supply. The said body, also at a point below the extension 11, is formed with a duct 14 whose threaded portion 15 may be connected in the usual manner with the source of cold water supply. The two ducts 12 and 14 are separated from each other by means of a web 16. The said valve body is provided with a flange 17 threaded at 18 for the 85 reception of the lower reduced end of a sleeve 19 which extends axially into the extension 11, the said sleeve being relatively short so that its upper end terminates an appreciable distance below the top of said extension. 90 This sleeve is formed with an annular flange 20 which bears against radial projections 21 formed at the base of what we have elected to call a cylindrical dividing member 22, the 95 said flange 20 operating clamp-like to hold 100

the base of the dividing member against the gasket 23. This gasket is permanently seated upon a flange 24 formed within the body member 10 as a part thereof. In this manner, 5 the sleeve 19 which is stationary at all times functions to maintain a stationary position of the dividing member within the extension 11. The purpose of this arrangement will be appreciated as the description goes forward. 10

The sleeve 19 is formed with a worm screw 25 whose threads co-act with an interior thread 26 of a rotary cylindrical nut 27. This nut is permanently connected at its upper end with the base of a rotary stem 28 by means of a pair of diametrically opposed webs 27a to provide intervening orifices 33 as clearly shown in Fig. 2. Above the nut the stem is provided with a disk valve 29 whose lower face is provided with a gasket 30 adapted to bear against an inwardly flared upper extremity 31 of the dividing member 22, as shown in Figure 1. In addition to the said valve disk 29, which is adapted to co-act 25 with the dividing member 22, the stem 28 is shown as being equipped with a valve element 32, the latter adapted to co-act with the interior walls of the sleeve 19 at the top of the latter, as illustrated in Figures 1, 3 and 4.

30 The nut 27 is spaced vertically from the interior walls of the dividing member 21, and as illustrated the vertical exterior walls of the dividing member are spaced vertically from the interior vertical walls of a cylindrical valve 34, the latter carried by a sleeve 35 which is telescoped within a bushing 36 carried by the extension 11. This sleeve 35 extends out of the bushing 36 and fixed to the sleeve is a controlling handle 37. The stem 40 28 hereinbefore referred to has a free end provided with a controlling knob 38 which may be turned manually to effect the respective adjustments of the valves 29 and 32 with respect to their mating seats.

45 The valve body 10 is provided between the ends of its extension 11 with diametrically opposite connections 39 and 40, the former adapted to be joined by the customary packing to a bath shower head and the latter to a 50 discharge faucet of any well-known approved design. The cylindrical valve 34 is provided with a port-way 41 adapted to coincide with either one of the connections 39 and 40, depending upon an adjustment of 55 the sleeve 35. In other words, and by virtue of this means, the liquid to be discharged may be directed selectively to either one of these connections 39 and 40.

60 It is stated that an important object of the invention resides in the provision of a novel, positively-acting mechanism that will insure a delivery of hot water without fear of its being in the least intermingled with cold water or vice versa, together with an arrangement of instrumentalities that will permit

graduated amounts of hot water to be mixed with cold water, in order that water at just the desired temperature may be delivered at the discharge point of the mechanism. Reference may now be had to Figure 1 of the 70 drawings, wherein the valve disk 29 is seated against the upper edge of the dividing member 22 while the valve element 32 is positioned within the vertical bore of the sleeve 19. Before further proceeding, it is described 75 that the bore of the sleeve 19 opens at its lower end into the duct 12 and that its upper end is adapted, when the element 32 is in an unseated position, to open into the space A above said dividing member. With the parts in the position shown in Figure 1, which may be set forth as the normal position of the valve mechanism, both of the valves are closed so as to prevent water from the connections 13-15 from in any way finding egress from 80 the mechanism. The same would apply to the position of the parts shown in Figure 3 of the drawings. In Figure 4, it will be observed that the valve disk 29 has been lifted so as to space it from the upper edge of the 85 dividing member 21. It will further be observed that the valve element 32 has been lifted to a slight extent from the bore of the sleeve 19, but that it still functions valve-like to prevent any flow of water from the 90 mechanism by way of the duct 12. With the valve disk 29 in its described position, cold water is permitted to enter the dividing member through the radial base ports B thereof, 95 so that it may flow in an upward direction through the dividing member, thence from the member into the space between the member and the rotary valve 34, thence to either the discharge faucet of the mechanism or the shower connection, as may depend upon a 100 previous adjustment of the said valve 31. Cold water only is now being discharged from the mechanism without fear of its being intermingled with hot water.

105 On reference to Figure 5, it is observed that the valve 29 has been lifted to a greater distance above the upper edge of the dividing member 22 and that in so doing the valve element 32 has been entirely withdrawn 110 from the bore of the sleeve 19. Hot water is now permitted to flow through the sleeve simultaneously with the operation of flowing of the cold water, so that the latter and the former will mix within the valve 34 to be discharged from either the faucet or the shower connection, as may depend upon a previous 115 adjustment of said valve 34.

120 On reference to Figure 6, the disk 29 has been advanced upward to a still greater distance from the upper edge of the dividing member 22 and in view of the fact that the cylindrical nut 27 is carried by the valve stem 28 and that the outer diameter of the nut is in agreement with the inner diameter 125 of the dividing member, at the flare of the

latter, said nut itself acts valve-like to close the mechanism from the source of cold water supply. Therefore, hot water may be discharged from the mechanism without in any

way being mixed with the cold water. It follows, from the niceties of construction, that the respective valve adjustments can be graduated so that hot water only can be delivered from the mechanism or cold water only, or a mixture of hot and cold water, and at temperatures that would suit the purpose.

The sleeve 19 is formed with a keyway 19a adapted to receive a key (not shown), so that same may be manually applied to or removed from the flange 17 as desired. The elements 17, 27 and 26 are so designed that they may be readily incorporated in valve structures of well known types without requiring changes in the construction thereof.

23 We claim as our invention:

1. Valve mechanism comprising a body having hot and cold water inlet connections, respectively, the said body provided with a plurality of outlet connections, means for opening or closing either or both of the outlet connections, means in communication with the cold water inlet, means in communication with the hot water inlet, a plurality of rotary valves in co-action with the respective second and third named means adapted to be progressively controlled to admit of the discharge of hot or cold water or hot and cold water from either of said outlet connections, and a rotary stem common to all of said valves for rotating the valves together.

2. Valve mechanism comprising a body having a plurality of liquid inlet connections, a sleeve opening to one of the connections, a member surrounding the sleeve and having its walls spaced therefrom, the said member opening to the other of said connections, a plurality of axially movable valves in co-action with the sleeve and said member, and means common to all of the valves to move same at one time but in graduated degrees with respect to said sleeve and said member so that when the valves are in one position, the sleeve will be open to its inlet connection while the member is closed to its inlet connection and vice versa, and whereby when the valves are in another position both inlet connections will be operatively opened to the member and sleeve, respectively.

3. Valve mechanism comprising a body having normally non-communicating liquid inlet connections, a sleeve communicating with one of said connections, a hollow member embracing the walls of the sleeve and spaced therefrom and communicating with the other said connection, the body having discharge connections, a rotary valve for the discharge connections, said rotary valve forming a mixing chamber in co-action with the sleeve and said member, and a plurality of valves independent of said rotary valve arranged in co-

action with the sleeve and said member so that either or both of said inlet connections may be opened to said rotary valve.

4. Valve mechanism comprising a body having normally non-communicating liquid inlet connections, a sleeve communicating with one of said connections, a hollow member embracing the walls of the sleeve and spaced therefrom and communicating with the other said connection, the body having discharge connections, a rotary valve for the discharge connection, said rotary valve forming a mixing chamber in co-action with the sleeve and said member, a plurality of valves independent of said rotary valve arranged in co-action with the sleeve and said member so that either or both of said inlet connections may be opened to said rotary valve, and a single valve stem for said plurality of valves.

5. Valve mechanism comprising a body having normally non-communicating liquid inlet connections, a sleeve communicating with one of said connections, a hollow member embracing the walls of the sleeve and spaced therefrom and communicating with the other said connection, the body having discharge connections, a rotary valve for the discharge connection, said rotary valve forming a mixing chamber in co-action with the sleeve and said member, a plurality of valves arranged in co-action with the sleeve and said member so that either or both of said inlet connections may be opened to said rotary valve, and a single valve stem for said plurality of valves, one of the plurality of valves being threadedly connected with the sleeve and adapted when in one position to close the said hollow member against the flow of liquid therefrom.

6. Valve mechanism comprising a body having normally non-communicating liquid inlet connections, a sleeve communicating with one of said connections, a hollow member embracing the walls of the sleeve and spaced therefrom and communicating with the other said connection, the body having discharge connections, a rotary valve for the discharge connection, said rotary valve forming a mixing chamber, in co-action with the sleeve and said member, a plurality of other valves arranged in co-action with the sleeve and said member so that either or both of said inlet connections may be opened to said rotary valve, and a single valve stem for said plurality of valves, one of the plurality of valves being threadedly connected with the sleeve and adapted when in one position to close the said hollow member against the flow of liquid therefrom, another one of said plurality of valves being free to move respectively into and out of the sleeve to determine the flow of liquid from the latter, and a third one of said plurality of valves adapted to close against one end of said hollow member and to co-act with the last said valve to pre-

vent the flow of liquid from either of said inlet connections.

7. A valve structure having a plurality of inlet ports, a pair of axially positioned spaced apart members, respectively opening to said inlet ports and having discharge ends, and means movably mounted between said members and having portions adapted to co-act with said discharge ends for respectively opening and closing same with respect to said inlet ports of said structure, one of said members having means adapted for removable connection with the valve structure and means for engaging the other member so that both members are held normally in relatively stationary positions with respect to their respective ports.

8. A mixing valve comprising a body having a pair of inlets and an outlet, a sleeve opening to one of the inlets, a member surrounding the sleeve in spaced relation thereto and opening to the other inlet, a plurality of valves for controlling the discharge of fluid from the sleeve and member to the outlet and by which either the sleeve or member or both can be opened or closed to the outlet, one of the valves being mounted on the sleeve for movement in coaction with the sleeve and operable when in one position to prevent the discharge of fluid from the member to the outlet, and a single actuator for the valves.

9. A mixing valve comprising a body having a pair of inlets and an outlet, a sleeve opening to one of the inlets, a member surrounding the sleeve in spaced relation thereto and opening to the other inlet, a plurality of valves for controlling the discharge of fluid from the sleeve and member to the outlet and by which either the sleeve or member or both can be opened or closed to the outlet, one of the valves being threadedly mounted on the sleeve and operable when rotated to one position to close the member against the discharge of liquid therefrom to the outlet, and a single actuator for the valves.

10. A mixing valve comprising a body having a pair of inlets and an outlet, an open-ended sleeve fixed in the body to communicate with one of the inlets for the flow of fluid from the latter through the sleeve, a hollow member fixed in the body in surrounding spaced relation to the sleeve to provide a passage communicating with the other inlet for the flow of fluid from the latter through the member, valves for controlling the flow of fluid from the sleeve and member to the outlet and by which either the sleeve or member or both can be opened or closed to the outlet, one of the valves including a nut threaded on the sleeve and by which the valves are actuated to control the flow of fluid from the sleeve and member in response to rotation of the nut, the nut being operable when rotated to one position to prevent the

flow of fluid from the member, and a single actuator for the valves.

11. A mixing valve as embodied in claim 10 wherein the nut is provided with a port through which fluid from the sleeve is adapted to flow into said passage when the valve controlling the sleeve is open. 70

12. A mixing valve as embodied in claim 10 wherein the sleeve is provided with a reduced portion threaded into the body to 75 fixedly secure the sleeve in the body and is provided exteriorly with a shoulder engaging the member to clamp the latter in a fixed position in the body.

13. A mixing valve as embodied in claim 10 wherein one of said valves is in the form of a disk adapted for flatwise engagement with an end of the hollow member to close the latter to the outlet, and another valve is adapted to be received in an end of the sleeve to close 80 the latter to the outlet. 85

14. A mixing valve as embodied in claim 10 wherein the member is provided with an opening in which the nut is adapted to enter when rotated to said position so that the nut 90 closes the member against the flow of fluid therefrom to the outlet. 95

15. A mixing valve comprising a body having a pair of inlets and an outlet, a sleeve fixed in the body and being in communication with one inlet for the flow of fluid therefrom through the sleeve, a hollow member fixed in the body in surrounding spaced relation to the sleeve to provide a passage communicating with the other inlet for the flow of fluid from the latter through the member, a plurality of valves for controlling the flow of fluid from the sleeve and member, means for mounting the valves for combined rotary and axial movements as a unit, to occupy one position wherein one valve closes the sleeve to the outlet and another valve closes the member to the outlet, a second position wherein the first valve maintains the sleeve closed to the outlet and the second valve 100 opens the member to the outlet, a third position wherein the first valve opens the sleeve to the outlet and the second valve maintains the member open to the outlet, and a fourth position wherein the first valve maintains the sleeve open to the outlet and a third valve 105 closes the member to the outlet, the said mounting means for the valves comprising a nut threadedly mounted on the sleeve and constituting the third valve, and a single 110 actuator for the valves. 115
